BRACKET FOR ELECTRICAL CONDUCTOR CHANNELS

Donald Alfred Sloan, Winston-Salem, N.C., assignor to
Envirotech Corporation

Filed Mar. 25, 1974, Ser. No. 454,994

Term of patent 14 years

Int. Cl. D8—08

U.S. Cl. D8—229

FIG. 1.

FIG. 2.

FIG. 1 is a perspective view of a bracket for electrical conductor channels showing my new and original design, the insulating conductor channels therefor being indicated in phantom lines for illustrative purposes only.

FIG. 2 is a perspective view from the opposite side of the bracket for electrical conductor channels shown in FIG. 1.

I claim:

The ornamental design for a bracket for electrical conductor channels, as shown and described.
